UNITED STATES PATENT OFFICE.

SAMUEL AUSTIN DUGAN, OF GALVESTON, TEXAS.

LOCOMOTIVE-ENGINE-CUT-OUT VALVE.

1,145,757.

Specification of Letters Patent.

Patented July 6, 1915.

Application filed May 15, 1914. Serial No. 838,713.

To all whom it may concern:

Be it known that I, SAMUEL A. DUGAN, a citizen of the United States, and a resident of Galveston, in the county of Galveston and State of Texas, have invented a new and Improved Locomotive-Engine-Cut-Out Valve, of which the following is a full, clear, and exact description.

This invention relates to locomotives and deals more especially with valves for cutting out either engine of the locomotive under certain emergency conditions whereby the locomotive can still be run to a point of repair or to the end of the route.

The invention has for its general objects to improve and simplify the construction of valve mechanisms of the character referred to so as to be thoroughly reliable and efficient in use and comparatively simple and inexpensive to manufacture and install without requiring any change in the standard design of piping or smoke box construction.

A further object of the invention is the provision of a valve in each branch of the Y-coupling between the dry pipe and branches that lead to the locomotive engines, whereby either one of the latter can be cut out of use in case of a breakdown of such engine.

Another object of the invention is the provision of means whereby the valves can be operated from the locomotive cab so that the valves cannot only be conveniently manipulated but they may be used for controlling the running of the locomotive when the throttle valve is unserviceable for any reason.

A further object is the provision of cut-off valves at the point where the dry pipe branches to the engines, so that at the end of a run, or when the locomotive is to be put up for the night, the branches or breeches pipe can be closed so that water of condensation will not drain into the engine cylinders and necessitate the removing of the water of condensation from such cylinders when the locomotive is to be again used.

With such objects in view, and others which will appear as the description proceeds, the invention comprises various novel features of construction and arrangement of parts which will be set forth with particularity in the following description and claims appended hereto.

In the accompanying drawing, which illus-

trates one embodiment of the invention and wherein similar characters of reference indicate corresponding parts in all the views, Figure 1 is a side view of a front portion 60 of a locomotive with a part of the shell broken away to expose the engine cut-out valve mechanism; and Fig. 2 is an enlarged sectional view through the smoke chamber of the locomotive with part of the breeches 65 pipe and Y-coupling in section.

Referring to the drawing, A designates the boiler of a locomotive, B the smoke bonnet, C the engines, D the steam dome, E the dry pipe, F and F' the branches and breeches 70 of the dry pipe that lead to the engines of the locomotive, and G the Y-coupling that connects the dry pipe with the branches. All of the foregoing parts are of usual construction with the exception of the coupling G.

The lateral branches g and g' of the Y-coupling are each formed with a partition 1 in which is a valve seat 2, and arranged to engage the seat 2 is a valve 3 fastened to 80 a stem 4 that is operated in any suitable manner to open and close the valve from a point outside the smoke chamber B. In the present instance the stem 4 passes through a stuffing box 5 and has a screw 6 which is 85 engaged by a nut 7, said nut being rotatably mounted in a bearing 8 of the bracket 9 or other suitable support mounted on the Y-coupling G. By turning this nut 7 the valve stem 4 is moved longitudinally to open 90 or close the valve 3. Under normal condition the valves of both branches of the Y-coupling G are open, so that steam can flow to the engines of the locomotive, according 95 to the manipulation of the throttle valve by the engineer. If, however, the piston or cylinder, link motion or driving connections of any engine are deranged, the engineer can cut that engine out of service by closing the 100 valve 3 therefor and continue to drive the locomotive by using the other engine.

It is preferable to provide means whereby the engine cut-out valves may be operated from the engine cab H, and for this purpose a shaft 10 extends from each valve to 105 the cab, and on the rear end of each shaft is a handwheel or equivalent operating means 11, and on the front end of each shaft is a bevel gear 12 which meshes with a bevel gear 13 fastened to the nut 7 for the 110 associated valve 3. Not only are the engine cut-out valves useful in case of a break-

down of an engine, but when the locomotive is to be put away for the night the valves 3 can be closed before the engineer leaves his cab, and thereby water of condensation 5 is prevented from draining into the engines.

From the foregoing description taken in connection with the accompanying drawing, the advantages of the construction and method of operation will be readily understood by those skilled in the art to which the invention appertains, and while I have described the apparatus which I now consider to be the best embodiment thereof, I desire to have it understood that the apparatus 10 shown is merely illustrative and that such changes may be made when desired as are within the scope of the appended claims.

Having thus described my invention, I claim as new and desire to secure by Letters 20 Patent:

1. In a locomotive, the combination of driving engines, a boiler, a horizontally-disposed dry steam pipe, a smoke-box into which the pipe extends, branches in the 25 smoke box and leading from the pipe to the engines, a Y-coupling uniting the branches with the dry steam pipe, and valves in the Y-coupling for opening and closing the supply of steam to the branches.

2. In a locomotive, the combination of driving engines, a dry steam pipe, branches connected with the engines, a Y-coupling uniting the branches with the dry steam pipe, valves in the Y-coupling for opening 30 and closing the supply of steam to the branches, and means connected with the respective valves and extending to the locomotive cab for permitting the valves to be operated by the engineer.

3. In a locomotive, the combination of a 40 boiler, a smoke box, a dry steam pipe in the boiler, pipes in the smoke box and connected with the dry steam pipe, driving engines receiving steam from the branches, and separate valves at the points of union of the 45 branches of the dry steam pipe whereby either or both branches may be closed.

4. In a locomotive, the combination of a 50 boiler, a smoke box, a dry steam pipe in the boiler, pipes in the smoke box and connected with the dry steam pipe, driving engines receiving steam from the branches, 55 separate valves at the points of union of the branches of the dry steam pipe whereby either or both branches may be closed, and an operating mechanism for each valve and including means extending to the cab of the locomotive.

5. In a locomotive, the combination of 60 driving engines, a boiler, a smoke box, a dry steam pipe in the boiler, branch pipes connected with the engines, a Y-coupling connecting the upper ends of the branches with the dry steam pipe, valves in the coupling for opening and closing the communication between the branches and dry steam pipe, stems on the valves extending out of the Y-coupling and out of the smoke box, and operating shafts operatively connected with the valve stems and extending to the 65 cab of the locomotive.

In testimony whereof I have signed my name to this specification in the presence of two subscribing witnesses.

SAMUEL AUSTIN DUGAN.
